UNITED STATES PATENT OFFICE.

ROBERT GOLDE, OF BROOKLYN, ASSIGNOR TO THE ROYAL METAL MANUFACTURING CO., OF NEW YORK, N. Y.

DESIGN FOR A PICTURE-FRAME, &c.

SPECIFICATION forming part of Design No. 22,977, dated December 19, 1893.

Application filed November 13, 1893. Serial No. 490,844. Term of patent 8½ years.

To all whom it may concern:

Be it known that I, ROBERT GOLDE, a subject of the Emperor of Germany, residing at Brooklyn, in the county of Kings and State 5 of New York, have invented and produced a new and original Design for Picture-Frames and the Like, of which the following is a specification, reference being had to the accompanying drawing, forming part thereof.

10 The drawing shows a plan view of my design adapted for picture frames, plaques and the like, one half (the upper) showing the outline plus the surface ornamentation, the other half (the lower) showing the outline or configuration.

15 My design consists in a border comprising the bars 1 having a configuration and surface ornamentation simulating the branch of a tree with the bark thereon the ends 2 of which are crooked the opposite end having the reverse curve 3, the crook 2 running into the first curve of the ends 3, each opposite end of the bars 1 overlapping the other as at 4. Extending from the crooks 2 are leaves, simulating oak leaves, as at 5, which extend the 20 length of the crooks 2 to that of the ends 3, making the border lines formed of the bars 1 and leaves 5 well balanced to the eye. From the ends 3 extend inwardly a leaf and spring

6 both following the general direction of such 30 ends; and between the ends 3 and crooks 2 at the top right and lower left hand corners extend a bunch 7 simulating grapes or berries, which bunch also merges into the leaves 5 at those corners. From the bars 1 between the 35 corners extend outwardly separate groups of overlapping leaves 8, the upper group having an additional leaf 9 to make a crowning effect to the upper part of the frame, and between the said leaves and on the bars are dispersed groups 10, of grapes, &c., and entwined about the bars at the corners and between them, are twists of a vine as at 11.

My design therefore consists of the three essential elements which are so combined as 45 to present to the eye the combined effect of the oak branches, leaves, with an intertwined creeping and fruiting vine.

Having thus described my design, I claim—

The design for picture frames, and the like, 50 substantially as herein shown and described.

Signed at the city, county, and State of New York this 11th day of November, 1893.

ROBERT GOLDE.
